UNITED STATES PATENT OFFICE.

EDWARD E. FLEMING, OF HAGERSTOWN, MARYLAND.

ENVELOPE OPENER.

Application filed July 6, 1926. Serial No. 120,781.

This invention relates to envelope openers.

It is a common practice to use a paper cutter or knife or pointed instrument adapted to be inserted in a crevice between the corners of the envelope and the flap for cutting or tearing apart portions of the envelope, with the result that the contents of the envelope are often cut or torn with consequent injury thereto.

10 One object of my invention is to provide an envelope opener that will not be liable to cut or otherwise injure the contents of the envelope, and which will enable the user to open one end or margin of the envelope 15 without injuring its contents and so as to permit anything it contains to be easily removed intact.

Another object is to provide a simple and efficient device of the character referred to, 20 whereby envelopes may be easily and quickly opened without danger of cutting, tearing or mutilating anything contained therein, by merely cutting a very narrow strip from one end or margin of the envelope so as to 25 leave it otherwise intact, which is impossible in using envelope openers such as are commonly employed.

The invention will first be hereinafter more particularly described, with reference 30 to the accompanying drawings, which are to be taken as a part of this specification, and then pointed out in the claims at the end of the description.

In said drawings, Fig. 1 represents a top 35 or plan view of an envelope opener embodying my invention;

Fig. 2 is a front elevation of the same;

Fig. 3 is an end view thereof;

Fig. 4 is a vertical transverse section taken 40 on the line 4—4 of Fig. 1;

Fig. 5 is a detail sectional view of the reciprocating carriage or knife-carrier;

Fig. 6 is a detail end view, and Fig. 7 a detail sectional view, illustrating the mode 45 of attaching an ordinary knife-blade of the safety razor type to one end of the reciprocating knife-carrier or carriage;

Fig. 8 is a detail view of the knife-carrying end of the carriage having means thereon for attaching an ordinary safety razor blade or knife; the knife being removed;

Fig. 9 is a perspective view of a modified 50 form of envelope opener embodying my invention;

Fig. 10 is a vertical transverse section of 55 said modification;

Fig. 11 is a fragmentary detail plan view of a modified form of the knife-carrier shown in Figs. 9 and 10; and

Fig. 12 is a perspective view of the knife- 60 carrier shown in Fig. 11.

Referring to said drawings, in which the same reference letters or numerals are used to denote corresponding parts in different views; the letter A in Figs. 1 to 4 denotes 65

a frame-structure on which is mounted a reciprocating knife-carrier or carriage and associated parts of an envelope opener embodying my invention. Said frame-structure, as shown, consists of a hollow casting 70 of substantially rectangular or oblong form having a top portion a¹, and a rear portion or wall a¹, together forming a rear portion of angular form in cross section, connecting opposite end-portions a², and also a bottom 75 cross-bar a³, at the front, formed integrally with enlarged end-portions or extensions a⁴ having integral upstanding terminal members a⁵, for a purpose hereinafter described.

The cross-bar a³ forms a rest or support for 80 the forepart of an oblong receptacle C arranged below the cutter and adapted to receive the strips cut from the envelopes; said receptacle being provided with a handle c and adapted to be easily removed and re- 85 placed when it is desired to empty the same. The upright members a⁵ of the frame-structure are suitably apertured to provide bearings for opposite ends of a rod D forming

one of what I term the rails of a track 90 along which the knife-carrier or carriage travels back and forth with a knife or cutter thereon in proper position for severing a narrow strip from the end or margin of an envelope placed in the path of movement of 95 the knife. D¹ denotes a transverse bar

parallel with the rod D and forming the other track rail; on which the free end of the carrier rests and slides back and forth; the latter bar serving the double purpose of a 100 track rail for the knife-carrier and as a stop to arrest the movement of an envelope inserted in position to adapt the knife to

cut a narrow strip from the end or margin of the envelope, without cutting or injuring its contents. E denotes a flat metal bar or plate placed flatwise beside and parallel with the combined track rail and stop bar D¹, and slightly separated from the front edge of the top a¹ of the frame structure so 105 that the cutting edge or end of a knife-blade fixed on the carriage may enter be-

110

tween said edge and the plate E, thus forming a knife-guide. The bar D¹ has depending end-portions or brackets d with apertured extremities in which are inserted 5 screws d¹ which enter oblong horizontal slots in upright members f of levers F, fulcrumed on the outer sides of opposite ends of the supporting frame, for depressing a presser-bar G when said levers are depressed; said oblong slots serving to compensate for any movement of the levers tending to force the bar D¹ into binding contact with the guide plate E by permitting the bar D¹ to move slightly up or down 10 while the screws d¹ move slightly forward or back as the levers are raised or lowered, thus providing sufficient play for the purpose stated. The free ends of the levers F are upturned and connected by a cross-bar or treadle F¹ adapted to be depressed by pressure of a finger thereon and thereby 15 depress the presser-bar G.

The knife-carrier comprises a base plate 1 having end plates 2 and 3 rigid therewith 20 and extending upwardly substantially at right angles thereto, and also a rocker-plate 4, arranged between the end plates 2 and 3 and having an operating handle 5 thereon. The end plate 2 has threaded apertures 30 therein to receive the ends of screws on which are fitted peripherally grooved rollers 6 adapted to travel along the rod D as the knife-carrier is moved back and forth and also has secured thereto brackets 7 of hook-shaped form with their curved or hooked ends underlying the rod D so as to pivotally 35 secure the knife-carrier on the rod while permitting sliding movement along the rod which is arranged in parallel relation to the track rail or bar D¹ on which the free end 40 of the knife-carrier is slidably supported so that it may be raised to raise the knife. Elbow-shaped brackets 8, bolted or otherwise secured to the upper edges of the end-portions of the frame A, have upstanding 45 end-portions 9 which may contact with and hold the track-bar D¹ in frictional contact with the guide-bar E. The upper edge of the 50 guide-bar E is arranged flush with the top a of the frame-structure A, or preferably flush with a metal plate H having its ends secured in recesses at opposite ends of said top. The plate H is preferably nickel-plated to provide a smooth and polished 55 surface underlying the presser-bar G between which and the plate H the end or margin of the envelope is inserted for opening the same. A shaft I arranged within the angular rear portion of the frame-structure 60 has its ends inserted through apertures in the end-portions of said frame and on the projecting ends thereof are secured peripherally roughened disks or milled-wheels K for rotating said shaft to depress the 65 presser-bar. The shaft I has secured

thereon or thereto the lower ends of links i the upper ends of which are secured to or on the ends of the presser-bar so that when the shaft is turned in one direction the 70 presser-bar will be depressed.

To the ends of the presser-bar are pivotally secured the ends of links g the other ends of which are pivoted to the levers F so that the presser-bar may be depressed by pressure upon the treadle bar F¹, or by slight 75 rotation of the disks K. To lift or restore the presser-bar to normal position a spring L has one end secured to a fixture l projecting from the cross-bar a², while the other end of the spring is secured to the free end 80 of an arm i² projecting from the shaft I, so that the presser-bar, when lowered and released, will be automatically raised and held normally in raised position. It may be desirable in some cases to use either the 85 treadle-bar F¹ or the milled-wheels K alone, or equivalent means on the shaft I for depressing the presser-bar, and one of these depressing means may be dispensed with.

The end plates 2 and 3 of the knife-carrier have aligned apertures therein to receive and provide bearings for a rockable bar or shaft 10 secured to the rocker-plate 4 on the underside thereof, as shown in Fig. 5. One end of the shaft 10 protrudes through an 90 aperture in the end plate 3, and said end is of polygonal form, as shown in Fig. 8, and has a threaded socket therein to receive a screw for securing thereto the assembled 95 parts of a knife-blade holder and interposed knife; said holder comprising an inner plate 11 having an opening therein intermediate its ends adapted to fit over the correspondingly-shaped protruding end of the shaft 10 and also having studs or projections 12 100 (Figs. 7 and 8) on opposite sides of said opening adapted to enter spaced registering holes in an outer plate 13 and an interposed knife-blade 3²; said outer plate and knife-blade also having intermediate holes registering with the interiorly threaded socket in the end of the shaft 10 for the insertion of 110 a screw 14, whereby the assembled parts are secured on the end of the shaft 10, so that when either end of the rocker-plate 4 is depressed one end of the knife-blade will be correspondingly depressed and caused to 115 enter the guide-slot between the guide-plate E and the plate H underlying the presser-bar in position for severing a strip from the 120 end of an envelope positioned in the path of the knife. A spring or springs may be interposed between the rocker-plate and the base plate 1, for holding the rocker-plate in a horizontal position and to restore the same 125 to such position when either end thereof has been depressed, and to this end I preferably employ a flat spring 15, (Fig. 5) of bow-shaped form, having its upwardly inclined 130 end-portions each bearing on the under side

of a projecting end-portion of the rocker-plate. To limit downward movement of the rocker-plate, if desired, set screws 16 may be inserted through apertures in the base-plate and secured in fixed positions by means of lock nuts 17 screwed thereon, and bearing against the under side of the base-plate.

The receptacle C is supported mainly on the front frame-bar a^3 ; and is sustained in a horizontal position by laterally projecting flanges c^1 , on opposite ends thereof, adapted to rest upon shoulders formed at the junction of the main portion of said frame-bar a^3 with the enlarged end-portions a^4 thereof, as shown in Fig. 2.

My invention in its broader aspects is illustrated in a simplified form in Figs. 9 to 12 of the drawings, in which the construction and arrangement of the assembled parts is substantially the same in all essentials as the construction and arrangement shown in Figs. 1 to 8, except that instead of a carriage or knife-carrier on wheels and an oscillatory knife-blade, the knife-carrier is slidably mounted on parallel bars independent of the stop bar D^1 , which, as shown in Figs. 1 to 4, serves the double purpose of a stop and a track rail.

In Figs. 9 and 10 the knife-carrier is shown slidably supported on parallel rods 20 and 21 and consists of a single piece of cast or sheet metal having integral apertured lugs 22 and 23 at the four corners thereof through which the rods 20 and 21 pass; the rod 20 being secured at opposite ends thereof to upstanding end-portions a^4 of the supporting frame, while the rod 21 is secured at opposite ends thereof to the ends 40 of links 25 which are carried by the rod 20 and project therefrom toward the knife, so that the knife-carrying end of the carriage may be raised and lowered to bring the knife into operable position in the same 45 manner that it is raised and lowered in the first mentioned construction. Instead of a rockable or oscillatory knife, a relatively fixed knife having a double cutting edge is employed, the knife being somewhat in the 50 form of the letter V, as shown, with its cutting edge arranged to enter the guide-slot and sever a strip from one end or margin of an envelope positioned in its path of movement in either forward or backward 55 direction. Pins 26 projecting from the inner sides of the end-portions a^4 of the supporting frame adjacent the rod 20 serve as rests for the links 25 to limit downward movement of the free end of the knife-carrier as it is moved forward and back along the track rails, as described with reference to Figs. 1 to 4 of the drawings.

It will be observed that in the modified form the assembled parts are arranged in a reverse position to that shown in Figs. 1

to 4; that is to say the angular portion of the supporting frame, denoted by the letters a and a^1 in Figs. 1 to 4, is arranged at the front instead of at the rear of said supporting frame, as in Figs. 1 to 4, while the cross-bar a^3 and receptacle C supported thereon are also arranged at the rear of said frame. The operating levers and treadle bar F^1 and presser-bar G and associated parts are substantially identical with the corresponding parts shown in Figs. 1 to 4.

In Figs. 11 and 12, the knife-carrying frame and associated parts are of substantially the same construction as the corresponding parts shown in Figs. 9 and 10, except that the sheet metal body of the knife-carrier has depending apertured lugs 27 at one end and upstanding apertured lugs 28 at the other end to receive the rods 20 and 21, so that the rod 21 is arranged above the plane of the rod 20.

While I preferably use as a knife or cutter a well known form of safety razor blade, to save expense, any other suitable form may be employed, either rotary, or relatively stationary, as may be found desirable in practical use, and various other changes may be made in the details and arrangement of parts without departing from the spirit and scope of my invention, and I therefore do not desire to be limited in the appended claims to the specific construction and arrangement shown and described.

Having thus described my invention, what I claim as new and desire to secure by Letters Patent of the United States is:

1. An envelope opener comprising a reciprocating carriage mounted on a supporting frame and carrying a knife blade adapted to operate when the carriage is moved in either a forward or backward direction, said carriage having a pivotal connection with said frame at one side or end while the opposite side or end thereof is free to be raised to raise the knife, a depressible presser-bar extending in a plane parallel with the line of movement of the knife adapted to hold an envelope with one end or margin thereof in position to be severed by the knife when moving in either direction, and means for depressing said presser-bar.

2. An envelope opener comprising a supporting frame having parallel bars thereon forming track rails, a reciprocating carriage carrying a cutter mounted on said rails, said carriage having a pivotal connection with one of said bars on which it may swing upwardly to raise the knife, a presser-bar adapted to hold an envelope in position to be cut as the cutter is moved along the track, and means for causing said presser-bar to hold the envelope in a fixed position during the operation of the cutter.

3. An envelope opener comprising a frame structure having parallel bars mounted

thereon, a reciprocating carriage slidably supported on said bars and carrying a cutter having a pivotal connection therewith whereby one end of the cutter may be thrown into operative position when the carriage is moving in either forward or backward direction, a presser-bar extending substantially parallel with said rails for holding an envelope inserted thereunder in position to permit the margin thereof to be severed by said cutter, and means for depressing said presser-bar; one of the first mentioned bars nearest the presser-bar serving as a stop to limit the movement of the envelope toward the cutter.

4. An envelope opener comprising a frame structure having parallel bars mounted thereon, a reciprocating carriage slidably supported on said bars and carrying a cutter having a pivotal connection therewith whereby one end of the cutter may be thrown into operative position when the carriage is moving in either forward or backward direction, a presser-bar extending substantially parallel with said rails for holding an envelope inserted thereunder in position to permit the margin thereof to be severed by said cutter, and means for depressing said presser-bar; one of the first mentioned bars nearest the presser-bar serving as a stop to limit the movement of the envelope toward the cutter, and a guide for the cutter beside the latter bar.

5. An envelope opener comprising a supporting frame having parallel bars thereon forming track rails, a reciprocating carriage mounted on said rails and carrying a rockable shaft, a knife-blade fixed on said shaft, a guide for said blade, and means for holding an envelope in position to be cut by the knife as it travels along said guide; said carriage having a hinge-like connection at one end with one of said bars and having its other end slidably supported on the other bar beside said guide.

6. In a device of the character described, a knife carrier arranged to travel back and forth along parallel bars and having a pivotal connection at one end with one of said bars while its other end is slidably supported on the other bar; said carrier having secured thereto a rockable shaft, an oblong knife-blade secured intermediate its ends to said shaft so that either end of said blade may be thrown into position to sever the margin of an envelope protruding into its path of movement.

7. In a device of the character described, the combination with a supporting frame having parallel bars thereon, a reciprocating carriage having a pivotal connection at one end with one of said bars and having its other end slidably supported on the other bar; said carriage having a rockable member thereon to which is secured a knife-blade

of oblong form, whereby said blade may be tilted to throw either end thereof into cutting position when the carriage is moving in either forward or backward direction, an operating handle on said carriage, and means for holding the margin of an envelope in the path of movement of the blade.

8. In combination, a frame structure having parallel bars thereon, a reciprocating carriage having a pivotal connection at one side or end with one of said bars while the opposite side or end thereof is slidably supported on the other bar, so as to adapt it to be raised to raise the knife and carrying a knife-blade, a guide extending parallel with said bars and adjacent to one of said bars, a pair of levers each fulcrumed on the frame structure at one end thereof, a presser-bar extending across the frame structure parallel with said bars and having a link on each end connecting it with one of said levers, and hand operated means for depressing said levers and thereby depressing said presser-bar.

9. In combination, a frame structure having parallel bars thereon, a reciprocating carriage mounted on said bars and carrying a knife-blade, a guide extending parallel with and adjacent to one of said bars, a pair of levers each fulcrumed on the frame structure at one end thereof, a presser-bar extending across the frame structure parallel with said bars, a link on each end of said presser-bar connecting it with one of said levers, a transverse bar connecting the free ends of said levers for depressing said presser-bar; one of the first mentioned bars nearest the presser-bar having its ends loosely connected to said levers between their fulcrums and the pivotal connections thereof with said links; said loose connections being adapted to prevent the levers from moving the last named bar into binding contact with said guide when the levers are depressed.

10. In a device of the character described, a knife carrier comprising a frame-bar having end plates arranged substantially at right angles thereto; said plates having aligned apertures therein, a rod or bar rockably fitted in said apertures and having a knife-blade detachably secured on one end thereof, and hand operated means on said carrier for tilting said blade to adapt either end thereof to be lowered into cutting position.

11. In a device of the character described, a knife carrier comprising a transverse frame-bar having end plates arranged substantially at right angles thereto; said plates having aligned apertures therein, a rod or bar rockably fitted in said apertures and having at one end a polygonal portion with an interiorly threaded socket therein protruding through the apertured plate, a plate having a polygonal opening therein fitting on the

- 5 polygonal end portion of said rod and having spaced projections thereon, an oblong knife-blade having correspondingly spaced openings fitted on said projections, an outer 50
- 5 plate having holes therein to receive said 55 projections, and a screw inserted in registering holes in the latter plate and knife and screwed into said socket for securing the knife to the plate.
- 10 12. In a device of the character described, a supporting frame having a reciprocating knife-carrier mounted thereon, a normally inoperative knife rockably mounted on said 60 carrier, and hand operated means for throwing a cutting edge of the knife into operative position when the carrier is moved in either forward or backward direction for severing a strip from the margin of an envelope arranged in the path of the knife, 65 and a detachable receptacle underlying the path of movement of the knife to receive the severed strips.
- 15 13. An envelope opener comprising a reciprocating carriage mounted on a supporting base and carrying a knife rockably mounted thereon and normally yieldingly sustained in inoperative position and adapted to be depressed to operate when the carriage is moved in either a forward or backward 70 direction, a knife-guide, and means for holding an envelope with one end or margin thereof in position to be severed by the knife when moving in either direction.
- 20 14. An envelope opener comprising a supporting frame having track rails thereon, a reciprocating carriage carrying a knife mounted on said rails, said carriage having a pivotal connection at one end thereof with one of said rails while its other end is 75
- 25 40 45 50 55 60 65 70 75 80 85 90 95
- slidably supported on the other rail a presser-bar extending parallel with and close to one of said rails between which and the top of said frame the end or margin of an envelope may be inserted and held in position to be severed by the knife; a knife guide beside the latter rail and hand operated means for forcing and holding the presser-bar down upon the envelope during the operation of the knife.
15. An envelope opener comprising a supporting frame having track rails thereon, a reciprocating carriage carrying a knife 50
- slidably mounted on said rails; and means for holding an envelope in position to be cut by the knife as it travels along said 55 rails; said carriage having a hinge-like connection at one side or end with one rail while the other side or end thereof is slidably supported on the other rail and adapted to be raised to raise the knife.
16. An envelope opener comprising a supporting frame having mounted thereon a knife adapted to present a cutting edge when moving in either forward or backward direction said knife being in the form 65 of an oblong blade rockably secured to a reciprocating carrier so that either end of the blade may be depressed into cutting position, and means for gripping and holding the envelope with the end or margin 70 thereof in position for the action of the knife.
17. An envelope opener comprising a supporting frame having mounted thereon a tilting knife secured to a reciprocating carrier and adapted when tilted to present a cutting edge when moving in either forward or backward direction, manually operated means for tilting the knife, a knife-guide, a stop to limit movement of the envelope 80 beyond a given point, and means for gripping and holding the envelope with the end or margin thereof in position for the action of the knife.
18. In a device of the character described, 85 a supporting frame having a reciprocating knife-carrier mounted thereon, a knife rockably mounted on said carrier normally in inoperative position, and hand operated means for exerting a rocking action and 90 throwing a cutting edge of the knife into operative position when the carrier is moved in either forward or backward direction, for severing a strip from the margin of an envelope arranged in the path of movement 95 of the knife.

In testimony whereof I affix my signature.
EDWARD E. FLEMING.
